UNITED STATES PATENT OFFICE

FRED AUTEM, OF WYOMISSING, PENNSYLVANIA, ASSIGNEE TO TEXTILE MACHINE WORKS, OF WYOMISSING, PENNSYLVANIA, A CORPORATION OF PENNSYLVANIA

BRAIDING MACHINE

Application filed July 14, 1930. Serial No. 467,789.

This invention relates to high speed braiding machines in which two sets of bobbins are rotated in opposite directions and the yarns of one set are situated over and under the bobbins of the other set in timed relationship; and more particularly to means for varying this timed relationship.

In order to remove the defects in the braid occurring at times during its production, it is necessary to reversely operate the machine and "unbraid" the material to the point of defect. This has heretofore been impracticable in the type of high speed machines to which the invention relates, because of the breakage of the yarns whenever the machine was reversely operated; such breakage resulting from the improperly timed relationship existing between the sinuating yarns and the bobbins over and under which they pass.

The primary object of my invention is to provide novel and simple means in a braiding machine of the type mentioned, for establishing the proper timing of the sinuating yarns and cooperating parts during reverse machine operation.

The invention comprises the novel elements, features of construction and arrangement of parts in cooperative relationship as fully disclosed by the following detailed description and accompanying drawings of one embodiment thereof, reference to which will make the above as well as other objects and attendant advantages more readily apparent.

In the drawings:

Fig. 1 is a fragmentary plan view of a known high speed braiding machine, certain parts being omitted and others broken away in order to more clearly show my invention, which is applied thereto.

Fig. 2 is a central cross-sectional view taken substantially as indicated by the arrows 2-2 on Fig. 1.

Fig. 3 is an enlarged fragmentary plan view of one of the yarn carriers of the upper set of bobbins and its surrounding parts, looking in the direction of the arrow 3 in Fig. 2, but with the carrier advanced 45 degrees from the position shown in said figure, and more particularly shows the relative positions of a sinuating thread from one of the

lower set of bobbins, for normal and reverse operation of the machine.

Fig. 4 is a plan sectional view of certain parts of my invention taken substantially as indicated by the arrows 3-3 on Fig. 2.

Fig. 5 is a view similar to Fig. 4, but of a modified form of construction.

Only certain essential parts of a high speed braiding machine have been indicated in the drawings. As well known, such machines mainly consist of an upper set of bobbins 10, which are unitedly rotated in one direction, and a lower set 11, rotated in the opposite direction, the threads from the latter set being situated over and under the bobbins of the upper set during machine operation; and the general construction shown and hereinafter described as preliminary to the setting forth of my present invention is well known in the art.

In the present instance, a thread guide slot 13 is provided for proper actuation of the lower bobbin threads T, which is formed between the edges of two spaced-apart stationary plates 15 and 16. The former being mounted on posts 17 rigidly secured to a base plate 18, and the latter fixedly mounted on a central support and bearing member 19, integrally formed on the base plate 18. The plate 15 is cut away at its front as indicated at 21, to facilitate the re-threading of the yarns T in case of breakage.

The plate 16 is provided with the usual concentric raceway 22, for the bobbins 10, and a cam groove 23 for oscillating the anchors 24 which are mounted on a revolvable bearing member 25. The active ends of anchors 24 alternately connect with notches in a respective bobbin carrier 10^a to take it along and permit the passing of the threads T therebetween.

The member 25 is secured to the upper end of a hollow shaft 26 journaled in bearing 19. Shaft 26 has a bevel gear 27 fixed to its lower end in mesh with a similar gear 28 on a drive shaft 29. Gear 28 also meshes with a gear 31 which is fixed to a circular plate 32 rotatably mounted on bearing 19 and carrying the lower set of bobbins 11. The gears 27 and 31 are of the same diameter so that rotation

of drive gear 28 moves the upper set of bobbins 10, and the lower set 11 in opposite directions at the same rate of speed.

In Fig. 3, A indicates the approximate proper position of a thread T which moves in one direction, in respect to a carrier 10 that moves in the opposite direction during normal or forward operation of the machine. It is in this connection that the present construction forming my invention is called for.

It will be apparent that if this relationship remains the same during reverse machine operation, the carrier of bobbin 10 will obstruct and prevent the passage of thread T along its guide slot 13. Consequently, it is necessary to shift threads T free of the carrier, or approximately to position B before reversely operating the machine.

To this end, I have mounted thread guide members or rods 33, over which the threads T pass, on a ring 34, and loosely connected the latter to plate 32 by providing therein slots 35 into which extend bolts 36, fixed in plate 32. In order to hold the ring 34 in the position illustrated in Fig. 4 during normal operation of the machine, i. e., so that threads T are in the position indicated at A in Fig. 3, two springs 37 are respectively connected to the rings 34 and plate 32, as shown.

If it becomes necessary to reverse the operation of the machine for the purpose mentioned, the drive shaft 29 is disconnected so that the machine can be manually and reversely operated by moving the lower set of bobbins 11 in the direction indicated by the arrow in Fig. 4. Handles 39 are provided for this purpose on ring 34. By pulling on these, ring 34 will first be rotated against the action of springs 37, until bolts 36 abut at the opposite ends of the slots 35, during which movement the guide rods 33 will be shifted and consequently threads T placed in position B in Fig. 3, after which ring 34 and plate 32 move in unison, and the movement of the upper and lower set of bobbins is reversed, through the gears described, while the threads T freely pass along in their guide slot 13. When handles 39 are released, springs 37 will automatically return the ring 34, rods 33, and consequently threads T to their normal position.

In Fig. 5, I have shown a modified form of my invention, the parts corresponding to those already described being indicated by the same reference numerals having the exponent "a". In this case the carriers 11a are directly mounted on the ring 34a, which is loosely connected with the plate 32a as before, however, instead of the springs 37 holding ring 34a in normal position, a spring pressed latch member 41 is provided on plate 32a, which cooperates with notches 42 in ring 34a to lock plate 32a and ring 34a together during normal and reverse machine operation.

Of course, other ways and means can be devised for attaining the invention herein set forth by one illustrative embodiment, without departing from its scope which is more particularly defined in the appended claims.

I claim:

1. In a braiding machine, the combination with two oppositely revoluble sets of bobbins, and means for sinuating the threads of one set over and under the bobbins of the other cooperating set in timed relationship; of means for relatively moving said sinuating threads and the cooperating set of bobbins to vary said timed relationship for reverse operation of the machine.

2. In a braiding machine, the combination with two oppositely revoluble sets of bobbins, and means for sinuating the threads of one set over and under the bobbins of the other cooperating set in timed relationship; of means for independently moving said sinuating threads relative to the cooperating set of bobbins to vary said timed relationship for reverse operation of the machine.

3. In a braiding machine, the combination with two oppositely revoluble sets of bobbins, and means for sinuating the threads of one set over and under the bobbins of the other set in timed relationship; of means for unitedly shifting the sinuating threads from the one set of bobbins relatively to the bobbins of the other set to vary the said timed relationship for reverse operation of the machine.

4. In a braiding machine, the combination with two oppositely revoluble sets of bobbins independently mounted and means for simulating the threads of one set of bobbins over and under the bobbins of the other set in timed relationship; of guide members for said sinuating threads, and means for varying said timed relationship for reverse operation of the machine including a support for said guide members adjustably secured to the mounting of one of said sets of bobbins.

5. In a braiding machine, the combination with two oppositely revoluble sets of bobbins, and means for sinuating the threads of one set of bobbins over and under the bobbins of the other set in timed relationship; of guide members for said sinuating threads, a mounting for said guide members secured for rotation with one of said sets of bobbins and adapted to be adjusted to vary said timed relationship for reverse operation of the machine, and means for retaining the mounting in its normal position.

6. In a braiding machine, the combination with two opposite revoluble sets of bobbins, and means for sinuating the threads of one set of bobbins over and under the bobbins of the other set in timed relationship; of guide members for said sinuating threads, a mounting for said guide members secured for rotation with one of said sets of bobbins and

- adapted to be adjusted relatively thereto to vary said timed relationship for reverse operation of the machine, and a spring for retaining the mounting in its normal position.
- 5 7. In a braiding machine having two sets of bobbins revolvable in opposite directions and means for sinuously traversing the threads of one set of bobbins over and under the threads of the other set, guide members revolvable in a path intermediate said sets of bobbins for positioning said traversing threads in timed relation to said revolving bobbins, and means operative upon reversal of said bobbin revolutions for rotatively 10 shifting said guide members relatively to vary the timed relation of the traversing threads.
- 15 8. In a braiding machine having two sets of bobbins revolvable in opposite directions and means for sinuously traversing the threads of one set of bobbins over and under the threads of the other set, guide members revolvable with one set of bobbins for 20 positioning said traversing threads in timed relation with the other set of bobbins, and means operative upon reversal of said bobbin revolutions for rotatively shifting said guide members relatively to vary the timed relation of their traversing threads.
- 25 9. In a braiding machine comprising two oppositely revolvable sets of bobbins, a stationary platform for one of said sets having a circular bobbin carrier runway and an endless thread passageway sinuously crossing 30 said runway, a revolvable platform for the other set of bobbins, thread positioning guide members for the latter mounted on said revolvable platform in shiftable rotatable relation thereto and traversed adjacent 35 said sinuous passage way in timed relation to the reversely revolving first series of bobbins, and means operated by reversal of said bobbin revolutions for relatively rotating said 40 guide members to differently position their timed relation to the reversely revolving first 45 set of bobbins.
10. In a braiding machine having two sets of bobbins revolvable in opposite directions and means for sinuously traversing the 50 threads of one set of bobbins over and under the threads of the other set, means for maintaining a timed relation of the threads of one set of bobbins relative to the other set of bobbins, and means for rotatively shifting 55 one set of bobbins preliminary to reversing the revolutions of both sets whereby the timed relation of the threads of said shifted set are varied with relation to the other set.

60 In testimony whereof I affix my signature.
FRED AUTEM.
